BOBBIN

Joseph Wallace Berry, Stourbridge, England, assignor to The Birmingham Aluminum Casting (1903) Company Limited, Birmingham, England, a British company

Application May 15, 1950, Serial No. 162,130
In Great Britain May 26, 1949

11 Claims. (Cl. 242—123)

1

The invention relates to bobbins, reels and the like more especially to those intended for use in the textile and allied trades.

A bobbin, reel, or the like in accordance with the present invention comprises a metal barrel and end flanges secured thereon, wherein the flanges provide at intervals abutments for the ends of the barrel and recessed seating portions to receive and seat upon the barrel ends and apertures through the flanges between the abutments in order that the barrel ends are accessible from the outside of the flanges when the latter are in position, which accessible portions are deformed behind parts of the flanges to secure the tubular barrel and flanges rigidly together.

It is preferred that the barrel and the flanges shall be made in a light metal such as aluminium or suitable alloys of aluminium or magnesium and the term "light metal" used in this specification is intended to include such alloys.

Other preferred features of the invention are set forth in the following description of examples of construction, in which reference is made to the accompanying drawings, and in the claims hereinafter appearing.

In the drawings:

Figure 1 is a sectional elevation of a bobbin the section being taken on the line 1—1 of Figure 3 and showing the assembled parts before the operation for securing the flanges is completed.

Figure 2 is a similar view to Figure 1 with the section taken on the line 2—2 of Figure 3.

Figure 3 is an end view of the bobbin looking from the left at Figure 1.

Figure 4 is a section on line 4—4 of Figure 5 showing one end of the bobbin after the securing operation has taken place.

Figure 5 is an end view looking from the left at Figure 5.

Figure 6 is a sectional view on line 6—6 of Figure 7 of a bobbin of modified construction.

Figure 7 is an end view of the bobbin shown in Figure 6 looking from the left.

Figure 8 is an end view looking from the right at Figure 6.

In the example of construction illustrated in Figures 1 to 5, the reference numeral 10 indicates the barrel of the bobbin, 11 is the left hand end flange and 12 is the right hand end flange. The barrel may be a drawn tube of light metal or one produced by die casting operation, but the drawn tube is more convenient for large sizes of bobbins. The flanges 11 and 12 are conveniently, but not necessarily, made as light metal castings preferably die castings. Each flange

2

is integral with a central boss 13 provided for mounting the bobbin in a machine for use. The greater part of this central boss is within the end of the barrel when the barrel and flanges are assembled and secured together. The central boss 13 and the flange (11 or 12 as the case may be) are rigidly connected together, in this example, by radial webs 14 extending from the boss to an outwardly directed circumferential rim 15. The central boss and the web are spaced apart as at 16 so that each flange has apertures passing through it from its inner face 17 to its outer face 18 between the webs and the inner faces of the webs 14 are recessed at 19 and, together, a seating is provided in the flange which enables it to be passed on to the end of the barrel and to fit thereon. The recess 19 in the webs 14 is deeper from the inner face of the flange to the abutment 20 at the end of the recess than the distance between the inner face 17 of the flange and outer face 18 between the webs. The end of the barrel passes through the apertures in the flange between the webs and projects beyond the outer face 18 of the flange as at 21, Figure 1, and provides substantial portions of the unbroken end which are accessible from the outer face of the flange and can be forced on to the surface 18 by drifts, punches, or like means into the position seen at 22 in Figures 4 and 5. The abutments 20 at the end of the deep recesses 19 in the webs 14 provide a fixed and rigid stop against the barrel ends and an exact location to give the desired axial separation of the flanges. The flanges are preferably pressed on to the barrel ends in a press and then the drifting or expanding operation to deform the barrel ends, is performed.

If desired the outer face 18 of each flange may be grooved or recessed (not shown) and the metal of the anchorage portions 21 of the barrel ends, which are expanded over the said face, are forced into the grooves or recesses to enhance the keying effect.

The flanges 11 and 12 are not necessarily the same in construction. As shown in Figures 1 and 2 the flange 11 is perpendicular to the barrel axis at its inner face 17, and the flange 12 has the inner face 17 slightly conical and the rim 15 is of different shape. The flanges will vary in size and design to adapt them to the particular purposes for which the bobbin is intended.

The number of apertures 16 and consequently of anchorages 21 around the circular seating of 55 the flanges will depend to some extent on the

dimensions of the bobbin or the like. The number should leave substantial webs 14 crossing the apertures 16 between the central boss and the circular seating of the flanges. Six anchorages 21 and webs 14 form a convenient arrangement for bobbins with barrels of about 1½" to 2" diameter and provide a very strong unit.

As shown in Figures 6, 7 and 8 the barrel 10 may be formed of one-piece of light metal tube having shapes that vary from the normal cylindrical tube and are formed by pressing, rolling or spinning operations.

By this means various shapes of barrel which offer advantages in use, may be produced as integral one piece tubular structures without any building up or assembly of additional parts to produce the shapes required.

In this illustrated example a barrel 10 formed of cylindrical tube is left cylindrical at one end and for part of its length is given a conical shape of larger diameter as at 23 near the other end which is reduced again at 24 to provide an integral cylindrical portion 25 for seating against its flange so that both ends are of even size and will fit flanges having circular seatings of the same size. The flanges 11 and 12 in this example are of unequal size while the seatings of the flanges at the two ends are of the same diameter, but obviously the seatings of the flanges 11 and 12 on the barrel ends may vary also to suit a barrel with different ends. The flange 11 is shown with small webs 26 across the angles of its rim 15 in between the radial webs 14, while the flange 12, apart from the shallow circular face 27 against which the barrel end 28 is expanded, is of entirely different section.

I claim:

1. A bobbin comprising a tubular metal barrel, end flanges for the barrel, a bearing boss integral with each flange, an annular wall of each flange surrounding and spaced from the bearing boss, spokes connecting said boss and wall and mainly disposed on the outer face of the wall, seatings in the spokes for the end of said barrel, said seatings communicating with the opening defined by the spacing of said boss and wall and terminating each in an abutment surface for engagement by the end of the barrel when passed through said opening, said seatings extending in an axial direction beyond the outer face of said wall, and circumferentially spaced portions of the end of the barrel located between said spokes being expanded to extend over a portion of the outer surface of said wall for securing the barrel and flange rigidly together.

2. A bobbin comprising a tubular metal barrel, end flanges for the barrel, a bearing boss integral with each flange, an annular wall of each flange surrounding and spaced from the bearing boss, a rim on the flange, spokes radiating from the boss to said rim, said spokes being mainly disposed on the outer face of the wall, seatings for the end of the barrel recessed in the spokes and communicating with the opening defined by said spaced boss and wall, said seatings extending in an axial direction beyond the outer face of said wall and terminating each in an abutment surface engaging the end of the barrel passed through said opening and seating, and portions of the end of the barrel located between said spokes being expanded to extend over a portion of the outer face of said wall between said spokes for securing the barrel and flange rigidly together.

3. A bobbin as specified in claim 2 in which

the spokes radiating from the boss to the rim connect said boss and wall.

4. In a bobbin having a tubular metal barrel, end flanges for the barrel each comprising a bearing boss, an annular wall surrounding and spaced from said boss, spokes radiating from the boss and connecting said boss and wall, said spokes being mainly disposed on the outer face of the wall, and seatings for the end of the barrel recessed in said spokes and communicating with the opening defined by said spaced boss and wall, said seatings extending axially beyond the outer face of the wall and terminating each in an abutment surface adapted for engagement with the barrel end when passed through said opening and seatings.

5. A bobbin as specified in claim 4 wherein a rim directed outwardly from the annular wall is provided, said spokes radiating from the boss to said rim.

6. A bobbin as specified in claim 1 wherein the barrel is provided with cylindrical end portions, a cylindrical body portion adjacent one end portion, and a flared body portion adjacent the other end portion, said flared portion being of a greater diameter than the cylindrical end and body portions of the barrel.

7. A bobbin as specified in claim 1 wherein the barrel is provided with cylindrical end portions, a cylindrical body portion adjacent one end portion, and a conical flared body portion increasing in diameter towards the other end portion, said flared portion having a diameter greater than that of the cylindrical end and body portions of the barrel.

8. A bobbin comprising a tubular metal barrel, end flanges for the barrel, bearing bosses and spaced connections joining said bosses one to each flange, a wall of each flange surrounding and spaced from the bearing boss to define with the latter an annular opening through which the end of the barrel is passed, seatings in said connections for the end of the barrel, and portions of the end of the barrel which protrude between said spaced connections being expanded to extend over a portion of the outer surface of said wall of the flange.

9. A bobbin comprising a tubular metal barrel, end flanges for the barrel each having a circumferential wall defining a central circular recess through which the end of the barrel is passed, a bearing boss entering the end of the barrel, said boss being spaced from the inner surface of the barrel, members integrally connecting said boss and wall, seatings in said members for circumferentially spaced portions of the end of the barrel, and further portions of the end of the barrel disposed between said circumferentially spaced and seated portions being expanded to extend over a portion of the outer surface of the wall of the flange to secure the barrel and flange rigidly together.

10. A bobbin comprising a tubular metal barrel, end flanges for the barrel, a wall of each flange defining a central circular opening through which the end of the barrel is passed, a bearing boss entering the end of the barrel and maintained in spaced relationship thereto by members radiating from the boss and integrally connecting the boss to the wall of the flange, seatings in said members for receiving circumferentially spaced portions of the end of the barrel, abutments on said members against which the circumferentially spaced portions of the end of the barrel abut when the end of the barrel is passed

through said opening to protrude beyond the surface of the wall, and portions of the end of the barrel intervening between said circumferentially spaced portions being expanded to extend over a portion of the outer surface of the wall of the flange to secure the barrel and flange rigidly together.

11. A bobbin reel comprising a metal barrel, end flanges for the barrel, a circumferential wall of each flange defining a central circular opening through which the end of the barrel is passed, a bearing boss received in and spaced from the barrel and means connecting said bearing boss and wall of the flange in such manner that the internal surface of the barrel is accessible from the outer face of the flange in order that por-

tions of the end of the barrel can readily be expanded to secure the flange to the barrel.
